UNITED STATES PATENT OFFICE.

CHARLES F. GAUNT, OF BIRMINGHAM, ENGLAND.

NAVAL, MILITARY, AND OTHER METALLIC BADGE.

1,353,228.

Specification of Letters Patent. Patented Sept. 21, 1920.

Application filed December 4, 1919. Serial No. 342,522.

To all whom it may concern:

Be it known that I, CHARLES FREDERICK GAUNT, of the city of Birmingham, England, a subject of the King of Great Britain, have invented certain new and useful Improvements in Naval, Military, and other Metallic Badges; and I do hereby declare that the following is a full, clear, and exact description thereof.

This invention has reference to military and other metallic badges. Heretofore metallic badges have been usually so designed that one part of the design must touch the adjacent part or parts of the same design so as thereby to hold the various parts of the design together and the cloth to which the badge is fixed does not show between the various parts of the design. For instance in the case of a design consisting of a shield surmounted by a crown and partly encircled by a wreath, such shield and wreath and crown would be made as one metal stamping but in close contact with one another and the cloth on which the badge is mounted would not show between the said shield and wreath and crown which would all appear as one piece of metal.

In the case of embroidered badges however the various parts of the design can easily be worked so as to be separated from one another with the black or other cloth showing between them.

Metallic badges have also heretofore been made in which the various parts forming the complete badge have been made separately of one another and then fixed at the proper distance apart on to a cloth covered back plate but this is comparatively tedious and expensive particularly when these badges are made in four or five separate pieces as each piece has to be mounted separately and at a correct distance from, and in the correct position relatively to the other pieces.

The object of my invention is to so manufacture metallic badges that the various parts of the design will form one piece but so constructed and arranged that the black or other material on which the badge is mounted, or material corresponding in color with that on which the badge is mounted, will show between the various parts or devices of the design which will in fact appear to be made and fixed to the cloth back separately from one another.

According to this invention the various parts of the design of a metallic badge for instance as a central shield part and a wreath partly encircling the same and a crown surmounting the same, are designed so as to be at a short distance apart from one another and these are connected together by any suitable number of small cross bars forming necks or bridges which are stamped or otherwise formed in a piece with the various parts of the design or are soldered or otherwise fixed thereto and these cross bars or bridges are covered with cloth or braid or sewing silk or any other suitable material corresponding with the cloth back to which the bridge is, or is to be fixed, so that when the badge is fixed on the said cloth back or cloth covered back plate the various parts of the design appear to be entirely separated from one another as the cloth, or the material of the same color as the cloth, shows between the various parts which do not appear to be in any way connected together.

For full comprehension however of my invention reference must be had to the accompanying drawings in which similar reference characters indicate the same parts and wherein:

Figure 1 is a front elevation of the metallic part of a naval badge formed of various devices connected together by integral small cross bars in accordance with this invention;

Fig. 2 is a front elevation of the same badge with these cross bars camouflaged and the whole badge mounted on its cloth back so that the various parts or devices forming the badge appear to be distinct from one another.

The badge shown on my drawings is of well known design and comprises the shield *a* bearing the anchor *b*, the shield being surrounded by the wreath *c* and surmounted by the crown *d*.

As will be seen by Fig. 1, these various devices *a*, *b*, *c* and *d* are situated at a short distance from one another and the shield *a* and wreath *c* are connected together by the small cross bars 1, two of which are on one side of the shield and two on the other side of the same and the shield is also connected to the crown *d* by a cross bar 2; the crown is connected to the ends of the wreath *c* by cross bars 3, also the anchor *b* is connected 110

to the interior of the frame of the shield *a* by the three cross bars *4*. The various devices *a*, *b*, *c* and *d* and their cross bars are stamped or otherwise formed together in one piece of metal as shown in Fig. 1. If desired however the shield, anchor, wreath and crown may be made separately from one another and connected together by the cross bars *1*, *2*, *3*, *4* being soldered or otherwise fixed thereto as shown. Or cross bars may be otherwise arranged. Before the badge Fig. 1 is mounted on its cloth back *e* as in Fig. 2 the cross bars *1*, *2*, *3*, are covered as aforesaid by sewing silk or other suitable material to match the cloth back *e* being wrapped around them so that when the badge is mounted on the cloth back as in Fig. 2 the cross bars are not visible unless the badge is examined very minutely. As the interior of the shield frame is filled in with red plush *f* the cross bars *4* which connect the anchor to the frame of the shield are covered with red sewing silk or other material wrapped around them so that the cross bars will not show against the red plush when the badge is mounted on its cloth back as aforesaid. Before being thus mounted a piece of blue velvet *g* is introduced at the back of the crown to show above the top of the same and through the perforations of the same as in Fig. 2.

The covering of the said bridges or cross bars *1*, *2*, *3* and *4* can be effected in any other suitable manner than by being covered with sewing silk, for instance each of the bridges or cross bars may be covered with a narrow piece of cloth or braid wound around the cross bar or such cloth or braid or other suitable material may cover only the front of the cross bar or bridge and can pass through holes in the cloth back or cloth covered back plate *h* to be fixed by sewing, cementing or other means. Or the cloth or other material covering the bridges or cross bars can be sewn or otherwise fixed to them so as to cover them as aforesaid.

Moreover if desired the covering of the cross bars can be effected at the same time that the badge is fixed on to its cloth back which is done by sewing silk or suitable material which is sewed through the cloth back or other back and over the cross bar and so on round and round until the cross bar is properly covered, the covering in this case assisting also to attach the badge to the cloth back.

Or instead of simultaneously sewing the badge on to the cloth mount and covering the cross bars by the sewing silk or other material as aforesaid, the badge at the cross

bars can be tied through the cloth and back plate of the badge by a piece of narrow cloth or other suitable material passing through two holes in the cloth and in the back plate at a short distance apart corresponding with the sides of the neck, the strip of cloth or other material covering the cross bars being drawn through and tied tightly or otherwise secured to the back of the back plate.

It is preferred however for the cross bars to be covered with sewing silk or the like as aforesaid before the badge is fixed to its cloth back and this fixing is preferably effected by the badge being furnished with upwardly projecting eyelet like parts which pass through holes in the cloth mount and in the stamped sheet metal back plate (not shown on our drawings) over which the ends of the eyelets are spread so as to thus secure the badge and the cloth back and back plate together.

As the color and texture of the cloth or other material which covers the cross bars as aforesaid corresponds with the color and texture of the cloth or other back mount it follows that when viewed from a short distance the said covering material of the cross bars cannot be distinguished from the cloth or other material of which the back mount is made.

It will be understood that the badge shown on my drawings is merely intended as an example and that my invention can be similarly applied to metallic badges of other designs.

What I claim is as follows:

1. The combination with a backing, of a metallic badge adapted to be mounted upon said backing and means covering parts of said badge and harmonizing in color with said backing whereby the visible parts of the badge appear disassociated from one another.

2. The combination with a backing, of a metallic badge adapted to be mounted upon said backing, said badge consisting of a plurality of devices, bars connecting said devices together, and a covering for each of said bars and harmonizing with said backing whereby the devices appear disassociated from one another.

In testimony whereof I have signed my name to this specification in the presence of two witnesses.

CHARLES F. GAUNT.
